UNITED STATES PATENT OFFICE.

MORTIMER N. JUDD, OF NEW BRITAIN, CONNECTICUT, ASSIGNOR TO THE NORTH & JUDD MANUFACTURING COMPANY, OF SAME PLACE.

DESIGN FOR A BUCKLE.

SPECIFICATION forming part of Design No. 14,606, dated February 5, 1864.

Application filed October 3, 1863. Term of patent 7 years.

To all whom it may concern:

Be it known that I, MORTIMER N. JUDD, a citizen of the United States, residing at New Britain, in the county of Hartford and State 5 of Connecticut, have invented and produced a new and original Design for a Buckle, of which the following is a specification, reference being had to the accompanying drawings, forming part thereof.

10 Figure 1 is a plan view of my newly-designed buckle, and Fig. 2 is a side elevation of the same.

15 A A designate the end bars, the same being flattened, with their upper surface slanting outward, as shown most clearly in Fig. 2. The edges of these end bars are straight and parallel with each other for the greater part

of their length, and until they nearly meet the side bars, thereby forming the rounded corners, as shown most clearly in Fig. 1. A round 20 cross-bar, b, extends from side bar to side bar, near the middle of their length, and on said bar is the part c, as shown.

I am aware of the buckles shown in Patent No. 160,912, and in Design Patent No. 2,570, 25 and I hereby disclaim the same.

I claim—

The design for a buckle, as herein shown and described.

MORTIMER N. JUDD.
